UNITED STATES PATENT OFFICE.

MAX BAECHLER, OF PARIS, FRANCE, ASSIGNOR TO BAECHLER, KISER & CIE., OF PARIS, FRANCE.

VERTICAL DRYING AND DEHYDRATING APPARATUS.

Application filed October 18, 1925, Serial No. 63,495, and in France October 21, 1924.

The present invention has for its object an apparatus adapted for drying all kinds of products, in which the substance to be dried is exposed to a stream of hot air in a particular manner. This apparatus is characterized by the combination, in the interior of a vertical cylinder, of metal truncated cones into which the material to be dried falls successively, with stationary plates on which turn blade devices mounted on a vertical shaft, the rotation of the said blades being adapted to cause the material to be treated to pass from one truncated cone to the next truncated cone through a stream of hot air which passes through the vertical cylinder preferably from the bottom to the top.

In the accompanying drawing there is illustrated solely by way of example one form of construction of the invention.

Figure 1 is a vertical axial section of the device.

Figure 2 is a plan view of one of the plates with its blade device.

As shown in the drawing, the apparatus consists of a stationary vertical cylinder 1 in which rotates a central vertical shaft 2. In the interior of the cylinder are mounted truncated cones 3 of sheet metal plates at suitable distances apart. These truncated cones, of which the large base is of the same diameter as the cylinder 1, are adapted to conduct the product 4 to be dried which they receive from the top towards the centre. Underneath each truncated cone is secured a horizontal plate 5 upon which rotates a blade device whose hub 6 is keyed to the shaft 2. The blades 7 of this device extend slightly beyond the outlet from the truncated cones 3, one or more 7' of these blades being extended to the periphery of the plate in such a manner as to completely remove from the latter the product to be treated. The hopper 8 from which leads a pipe 9 and a nozzle 10 is provided at the upper end of the cylinder 1. The lower portion 11 of the cylinder forms a collector for the dried materials. Into the lower portion there extends a fitting 12 which supplies hot air which escapes through the fitting 13 provided at the upper part of the cylinder outside the first truncated cone. The rotation of the shaft 2 and the blade devices is pro-

duced by means of a suitable motor through the medium of gearing 14.

The operation of the apparatus is as follows.

The material 4 to be dried, after having been charged into the hopper 8, falls through the pipe 9 and the nozzle 10 to the first stationary plate 5 from which it is moved slowly towards the periphery by the rotation of the first blade device 6, 7. The material then falls into the second truncated cone then into the third and so on until it reaches the chamber 11 from which it is removed in a dry condition by means of a suitable device such as a worm conveyor 15 for example. The stream of hot air which is drawn through the fitting 13, for example by means of a fan not shown, is supplied to the bottom of the cylinder 1 by the fitting 12 and firstly strikes against the lower plate which it heats energetically as also the material which has reached this plate. The hot air passes around the periphery of the plate and then into the lower truncated cone through free spaces formed by the blades during their rotation. This air then impinges upon the second plate and so on, from stage to stage, and finally escapes through the fitting 13. It will be seen that the drying is effected in a very economical manner by reason of the fact that the material is heated on the successive plates and also by reason of the fact that during its downward movement it moves in a direction opposite to that of the stream of hot air. No disadvantageous settling of the material can take place, as is the case in a number of vertical driers, and the escape of the steam is largely ensured by reason of the free passages provided for the air behind the blades due to the brushing away of the materials by means of these blades.

In connection with certain products it is possible to omit the distributor 9 whose operation, in such a case, is fulfilled by the first blade device. When the products to be treated are very moist openings may be provided in the upper parts of the truncated cones for the purpose of enabling a determined quantity of saturated air to be withdrawn directly without coming into contact with the products. This device has the advantage of effecting supplementary heating

of the saturated air at the top of the apparatus thus preventing condensation thereof.

The diameter and number of plates depend upon the output to be obtained or the nature of the product to be dried. The control of the output of material is obtained by means of a device not shown enabling the distance between the lower parts of the truncated cones and the plates to be varied. When devices are not provided with this adjusting device the output is controlled by the speed imparted to the central shaft.

It will be understood that the apparatus which has been described has only been given by way of example and that it is capable of being modified in detail without departing from the scope of the invention by reason of these modifications.

Thus for example the shape and the dimensions of the truncated cones as also that of the blade devices may be varied according to requirements and in some cases the plates and the cones may be perforated.

Moreover the stream of hot air may be caused to circulate in a direction opposite to that described.

Finally the apparatus may be provided with stationary blade devices combined with rotary plates.

In apparatus with stationary plates, the hub of the blade devices is secured to the shaft by a pin or key which, while ensuring the driving of the device, enables this to slide along the shaft. This method of connection has for its object to ensure perfect contact between the plate and the blade device by reason of the weight of the latter.

Independently of its use for drying any suitable material, the apparatus described may also serve as a dehydrator for gases or any suitable materials and more particularly for alcohol vapours. In the latter case the apparatus is completely heated and the plates may be perforated.

Having thus described my invention what I claim as new and desire to secure by Letters Patent is:—

1. A vertical apparatus adapted for drying and dehydration purposes comprising a vertical cylinder, a plurality of truncated cones mounted one above the other inside said cylinder, said truncated cones having a base equal in diameter to the internal diameter of the cylinder, and means for supplying and circulating hot air through said cones, a horizontal plate arranged underneath each cone, a vertically driven shaft extending centrally through the cylinder and through the cones, and blade devices co-operating with said plates, relative movement being permitted between the horizontal plates and the blade devices, and means for adjusting the relative position between the horizontal plates and the truncated cones. 55

2. Vertical drying and dehydrating apparatus for solids, gases and fluids comprising a vertical cylindrical casing, charging means at the upper end of said vertical cylinder, a conical collecting device at the lower end of said vertical cylinder, discharging means in said collecting chamber, a plurality of inverted truncated metal cones mounted one above the other inside said cylinder, the larger base of said cones being of the same diameter as the internal diameter of the cylinder, a vertical shaft extending centrally through said cones and said cylinder, means for driving said shaft, a plurality of horizontal plates arranged one underneath each cone, a plurality of blade devices arranged one above each plate and adapted to co-operate therewith, said plates being stationary whilst the blade devices are driven by said shaft, the blade devices being longitudinally movable on said shaft, and means for passing a stream of hot air through the interior of said cylinder. 75 80 85

MAX BAECHLER.
